UNITED STATES PATENT OFFICE.

ANTHONI ISKE, OF LANCASTER, PENNSYLVANIA.

IMPROVEMENT IN FIRE-ESCAPE LADDERS.

Specification forming part of Letters Patent No. 33,785, dated November 26, 1861.

To all whom it may concern:

Be it known that I, ANTHONI ISKE, of Lancaster, in the county of Lancaster and State of Pennsylvania, have invented a new and improved combination of section-ladders with upright extension sides mounted on wheels, constituting a fire-escape apparatus; and I do hereby declare that the following is a full, clear, and exact description of the construction and operation of the same, reference being had to the annexed drawings, making a part of this specification, in which—

Figure 1 is a perspective view, with the slatted compound levers down, one of the side arms F down the and other, with its rope and pulley, perpendicular. Fig. 2 shows the extension of the slats 1 to 19 with the section-ladders I, II to V in place, the platform 23 resting against the window-sill of a four-story dwelling with the several parts employed, being a profile view of one side only. Fig. 3 shows the supporting-frame B B'', &c., with its rack and pinion P M and windlass N, and the inside view of the lower slats and their connection, &c. Fig. 4 is a profile view of the same in part. Fig. 5 shows the manner of attaching the reel for the hose in part.

The object of this invention is to have a series of short ladders so constructed and suspended between the sides of the extension-elevators as with them to fold up and form a compact apparatus, sustained on a truck or carriage of the ordinary length, and also to admit of their elevation in a narrow alley in a perpendicular manner to any height from twenty to one hundred feet, and then inclined at any angle desired against a building, with its platform on top, to rescue persons from the upper stories of burning buildings, or to be used as a means of throwing water from a hose at such an elevated point—objects of the greatest utility in certain cases. To accomplish these objects I construct my apparatus in the following manner—viz., on a truck-frame supported by ordinary wheels, either curved on the sides, as shown by Fig. 6, so as to elevate the truss-frame and admit the front wheels beneath and facilitate the turning of the carriage, or made straight, as shown by Fig. 1, A A', &c. Within this truck-frame A, I suspend a truss-frame B B'', &c., by its pivots O near the forward end, while the rear is

supported by straps or chains wound upon a windlass D on the rear of the truck-frame between two uprights, as shown. The windlass is provided with a ratchet and click Z to hold or stay the same. There is also an iron S, either made to turn into or under the truss-frame held on the truck-frame, as shown by Fig. 2, for additional support, or a bar S with a series of holes on the truss-frame, held at any desired point by a bolt through the truck-frame, as shown in Fig. 3. The windlass D is used for the purpose of inclining the apparatus against a building or restoring it to its perpendicular position when so inclined. The sides of this truss-frame have a longitudinal slot I, Fig. 4, in which the rod K, connected on each side with a rack P, moves to and from the center by means of the pinions M on the shaft N, as shown. To this rod K the lower end of the expanding and contracting series of cross-levers or lazy-tongs marked 1 of each series is attached and moved by it with the rack. The rod L supports the lower end of the lazy-tong marked 2, and is affixed into the sides of the truss. On each side of the truss are a series of these parallel cross-levers or lazy-tongs, numbered 1 to 20, or more, if desired, held together by proper pins at their crossings, upon which they move. These two series are united at regular intervals by cross-ties, one of which is partly shown at O, Fig. 3, all moving simultaneously with the lower pieces 1 2 in being elevated or depressed, as aforesaid. (Shown extended and elevated by Fig. 2 and folded upon one another, as in Fig. 1, indicated by the red rod and lines, Fig. 3.) Between the two series of these extension-elevators, at regular intervals, is hung a short ladder, gradually narrowing upward—that is, so that the upper ladder may enter the next beneath it—between the side pieces or support of the rounds between them. These ladders are marked I, II, to V. The lower end of each ladder rests upon the upper round of the ladder below it. There is also a projecting piece x x, or several of them, on the back of the sides, which rest upon the rounds of the lower ladder next each at any point of elevation, keeping the ladders locked one upon the other when in use, thereby giving firmness and strength to the apparatus.

In order to unlock the ladders so as to lower

them, a rope VI is attached to the top or platform 23 and passed around the lower round of each section of the ladder and carried through a loop on the truck-frame. By extending this rope the ladders are drawn out, as shown by the red lines on Fig. 2, and allows the lazy-tongs to contact, carrying the ladders with them into the folded position shown by Fig. 1. On the shaft N there is also a ratchet and click R to aid in holding and regulate the motions of the elevators or lazy-tongs.

In large or weighty elevators, in order to facilitate the starting of the same, there is an arm F, with a pulley G at its top, affixed to the upright E by a pivot or pin, by which it can be laid down, as shown. There is also a pulley e on the inside of the upright E, Fig. 4. A rope H, attached to the upper series of lazy-tongs or levers on each side, passes around those pulleys and extends to the windlass C, on which they are held by a button. Thus by means of the windlass the elevators are easily raised to some height, where they will remain stationary. The ropes are then disengaged from the windlass and pulleys, and may then be used to steady, if need be, the apparatus while it is being extended to its utmost height by means of the racks and pinions and turn-handles on the sides. By having spikes h to the end of the ropes they may be driven into the ground and aid as braces, if desired. When thus elevated, the apparatus is easily inclined by means of the straps and windlass D in the rear against any roof or building for the various purposes contemplated in a fire-escape, &c. Fig. 6 also illustrates a better arrangement for raising the arm F and starting the lazy-tongs or levers by changing the pulley e and raising it on a stipe for the rope VI, to be wound on a separate pulley on the shaft of the hose-reel Y, thereby making it less liable to confusion in fixing the ropes H.

In order to save the expense of a separate hose-carriage, a reel Y for hose is attached to the rear of the truck-frame.

As it is desirable to remove the reel with the wet and dirty hose from close contact with the truck when washing the same, I propose to hinge the side arms v, Fig. 5, at x, which support the reel Y T, and secure the said side arms between an iron staple V of sufficient strength, having a screw-thread cut in its front union of the sides, with a handled screw W to confine said arms, respectively, or to allow the reel to be separated from the truck for the purpose named.

The facility with which this apparatus can be used and the great advantage it affords are readily comprehended, and it promises to be of the greatest utility in alleys or narrow courts, where long ladders cannot be run up against dwellings, and, in short, it presents altogether an apparatus greatly needed.

I am aware that the cross-slats or expanding and contracting levers are not new, and that they have been employed as extension-elevators in elevating persons, as well as other devices employed. I therefore do not claim any of the above-described devices separately considered.

What I claim as my invention, and desire to secure by Letters Patent, is—

1. The independent ladders, five or more in number, suspended by their upper ends on pivots between the elevating cross-levers, one above the other, successively narrowed, with their stay-catches x x, in combination with the rope VI, attached in the manner and for the purpose specified.

2. The truss or supporting frame B, with its jointed side pieces F F, when the same is held on pivots O between or inside of the frame A of the hose-carriage, with its reel Y operated by means of the windlass D and by straps d (or their equivalent) for the purpose of inclining the ladders, in the manner and for the purpose specified.

ANTHONI ISKE.
